UNITED STATES PATENT OFFICE.

GUSTAF JERNBERG, OF ROCKFORD, ILLINOIS.

MOWER.

SPECIFICATION forming part of Letters Patent No. 447,328, dated March 3, 1891.

Application filed September 18, 1890. Serial No. 365,429. (No model.)

To all whom it may concern:

Be it known that I, GUSTAF JERNBERG, a citizen of the United States, residing at Rockford, in the county of Winnebago and State 5 of Illinois, have invented certain new and useful Improvements in Mowers, of which the following is a specification.

The principal object of my invention is to provide improved means for raising, lowering, 10 and controlling the finger-bar of a mower by employing a counterbalancing-spring and auxiliary devices in connection therewith.

The minor objects of my invention will be fully stated hereinafter.

15 This invention consists of certain new and useful features of construction and combinations of parts hereinafter fully described, and specifically pointed out in the claims.

Referring to the accompanying drawings, 20 which form a part of this specification, Figure 1 is a plan view of a mower provided with my improvements. Fig. 2 is a front elevation of the same. Figs. 3, 4, and 5 are side elevations of the mower, fragmental, showing the different operations of the various levers thereof 25 on the finger-bar, the movements of the levers and finger-bar, and the parts connecting and co-operating with them being indicated by dotted lines. Fig. 6 is a view in isometric, 30 showing a cam for throwing the machine into and out of gear and a latch for locking the cover of the gear-case, both parts being actuated by the same spring. Fig. 7 is a section at the dotted line 7 7 in Fig. 3 of some parts 35 there shown. Figs. 8 and 9 are views in detail of parts shown in Fig. 1, which will be fully described hereinafter.

Like letters of reference indicate corresponding parts throughout the several views.

40 A A' A² A³ A⁴ A⁵ A⁶ are respectively the axle, wheels, frame, tongue, hinge-bar, finger-bar, and inner shoe of the mower, and are constructed, arranged, and connected together in the usual manner.

45 B is a rock-shaft, having bearings B' in the frame of the mower, and being provided with a counterbalancing-lever B², projecting upward therefrom, the lower end of said lever having segment-gear B³ thereon.

50 B⁴ is a ratchet-wheel integral and concentric with the rock-shaft B.

B⁵ is an equalizing-pulley arranged to move freely up and down in the recess B⁶ in the counterbalancing-lever B².

C is a tilting post rigidly connected with 55 the hinge-bar A⁴.

C' is a segment-pulley, having a groove C² in its peripheral portion mounted on the tilting post C between the ends thereof.

D is a gag-lever, pivotally mounted on the 60 shoe A⁶ at D' and controlling the finger-bar A⁵ in the usual manner.

E is a chain having axial connection with the equalizing-pulley B⁵, passing over a pulley E', mounted on the frame A² of the mower 65 and the segment-pulley C' and connecting with the upper end of the gag-lever D.

F is a ratchet-wheel mounted and revolute on and concentric with the rock-shaft B, and adapted to engage with its counterpart 70 ratchet-wheel B⁴.

F' is a counterbalancing-spring coiled about the rock-shaft B, having one end fast to the mower-frame at F² and the other end inserted into the slotted opening F³ in the periphery of the ratchet-wheel F. 75

F⁴ are holes for admitting a pin to wind up the ratchet-wheel F to increase the tension of the spring F'.

G is a foot lifting-lever, provided at its 80 lower end with the counterpart segment-gear G', meshing with the segment-gear B³, and mounted on the pivot-bearing G² on the mower-frame.

H is a hand lifting-lever, mounted on the 85 rock-shaft B and adapted to engage with the lug B' on the counterbalancing-lever B² whenever said hand lifting-lever is swung backward far enough to come in contact therewith.

H' is a segment-rack rigidly connected with 90 the mower-frame A².

H² is a detent connected with the hand lifting lever and adapted to engage with the segment-rack H'.

I is a draft-adjusting bar having hook connection at its lower end with the hinge-bar A⁴, and having its upper end passed through the slot A⁷ in the mower-frame A², wherein it may freely slide vertically, as indicated by 100 dotted lines in Figs. 4 and 5.

I' is a draft-clevis adapted to slide on the

tongue A^3 of the mower, whereto it is connected by means of a retaining-plate I^2 and a bolt I^3 , passed through a slot I^4 therein.

I^5 is a draft-rod having hook connection 5 with the draft-adjusting bar I and the draft-clevis I' by means of holes I^6 and an eye I^7 therein. Draft on the finger-bar A^5 may be increased by lowering and diminished by raising, respectively, the connection between the 10 draft-rod I^5 and draft-adjusting bar I , for which adjustment a series of holes I^6 therein provides.

J is a segment-rack rigidly connected with the mower-frame A^2 .

J' is a tilting-lever mounted on or near the base of the segment-rack J .

J^2 is a detent connected with the tilting-lever J' and adapted to engage with the segment-rack J .

J^3 is a tilting-rod connecting the lower end 20 of the tilting-lever J' with the upper end of the tilting post C .

K is a push-bar composed of two parts K' , and connecting the lower portion of the tilting post C with the lower end of the downwardly-extending arm A^8 , which is integral or rigidly connected with the frame A^2 of the mower. The tilting post C has a hole C^3 therein of greater diameter than the holes K^2 25 in the push-bar K . The arm A^8 also has a hole therein of greater diameter than the holes K^2 in the push-bar K .

K^3 is a bushing tapering at each end and inserted into the hole C^3 in the tilting post C .

K^4 is a bolt passed through the holes K^2 in the push-bar K and the hole K^5 in the bushing K^3 . The two parts K' of the push-bar K are secured to the ends of the bushings K^3 by means of the bolt K^4 and a nut K^6 . The connection of the push-bar K with the arms A^8 40 is the same as that just detailed. The construction shown allows the push-bar K free lateral rocking motion, as indicated by dotted lines in Fig. 7, which, taken together with the draft-adjusting bar I , having the connections with the mower-frame A^2 and hinge-bar A^4 , already shown, thereby permits greater freedom to the finger-bar A^5 in its vertical movements.

50 There is a train of gearing such as is ordinarily employed to transmit power from one of the wheels of a mower to the cutter-bar thereof contained in the case and cover A^9 A^{10} . L is one part of a clutch integral with the rear wheel L^2 of said train of gearing. L' 55 is a counterpart thereof adapted to engage therewith and be disengaged therefrom by sliding the same endwise on its shaft L^3 , as indicated by dotted lines in Fig. 6, to throw the mower into and out of gear.

L^4 is a shiftable-rod mounted and adapted to slide in a bearing A^{11} in the part A^9 .

L^5 is a shifter rigidly connected with the inner end of the rod L^4 and resting loosely in 65 the annular groove L^6 , located between the part L' of the clutch and the longitudinally-sliding gear-wheel L^7 .

L^8 is an actuating-spring holding the part L' when normal into engagement with the part L .

L^9 is a cam provided with a handle L^{10} , connected with the outer end of the rod L^4 by means of the pivot L^{11} and having an operative bearing on the outer end of the part A^{11} .

L^{12} is a latch capable of horizontal operation, as indicated by dotted lines in Fig. 1, loosely connected with the rod L^4 by means of a ring L^{13} , encircling the same, and actuated by the spring L^8 . The latch L^{12} engages with the slotted lug A^{12} on the cover A^{10} to 80 secure the same to the case A^9 .

Whenever the lever G is operated, the pulley B^5 travels downward in said recess B^6 , as indicated by dotted lines in Fig. 5, thus shortening the short arm of said lever G as the 85 finger-bar is raised, and thereby equalizing the power required to raise said finger-bar from the ground to its upper limit.

The wheels A' next to the observer are removed in Figs. 3, 4, and 5. The levers H J' 90 are also removed in Fig. 5.

The tension of the spring F' may be increased in the manner already stated until it will partially, nearly, or quite counterbalance the weight of the finger-bar A^5 and the 95 parts supported thereby, according as may be desired.

Whenever it is desired to partially raise the finger-bar to pass obstructions or turn corners in mowing, the operator will press his 100 foot on the foot lifting-lever G . If, however, it is desired to raise the finger-bar to its upper limit, the operator will press the hand lifting-lever H to supplement the work of the foot lifting-lever.

The finger-bar may be tilted backward and forward by means of the tilting-lever J' , as indicated by dotted lines in Fig. 3.

I claim—

1. In combination, the rock-shaft provided 110 with the counterbalancing-lever, the foot lifting-lever having segment-gear connecting therewith, the spring for actuating the counterbalancing-lever, the hand lifting-lever adapted to engage with and operate the foot 115 lifting-lever, the tilting post seated on the hinge-bar, the segment-pulley mounted on the tilting post between the ends thereof, the gag-lever, and the chain connection between the counterbalancing and gag levers, substantially as and for the purpose specified.

2. In combination, the rock-shaft provided 120 with an upwardly-extending counterbalancing-lever having a segment-gear on the lower end thereof and being provided with a recess 125 in its rear portion, the counterbalancing-spring coiled about the rock-shaft engaging with and actuating the counterbalancing-lever, the foot lifting-lever provided at its lower end with a segment-gear meshing with 130 the segment-gear of the counterbalancing-lever, the finger-bar, the equalizing-pulley arranged to move freely up and down in the recess in the counterbalancing-lever, and a

chain having axial connection with the equalizing-pulley and connecting with the finger-bar, substantially as and for the purpose specified.

5 3. In combination, the rock-shaft provided with the counterbalancing-lever having a recess in the back side thereof, the foot lifting-lever having segment-gear connection with the counterbalancing-lever, the spring for actuating the counterbalancing-lever, the hand lifting-lever adapted to engage with and operate the foot lifting-lever, the hinge-bar, the tilting post seated thereon, the segment-pulley mounted on the tilting post between the ends thereof, the finger-bar, the gag-lever mounted thereon, the equalizing-pulley arranged to travel up and down in the recess in the counterbalancing-lever, and the chain connection between the equalizing-pulley and gag-lever, substantially as and for the purpose specified.

4. In combination, the tongue, the hinge-bar, the draft-adjusting bar having loose con-

nnection therewith and sliding connection with the main frame or tongue of the mower, the draft-clevis adapted to slide on the tongue, and the draft-rod having loose vertically-adjustable connection with the draft-adjusting bar and loose connection with the draft-clevis, substantially as and for the purpose specified. 30

5. In combination, the shipper engaging with and adapted to operate the part clutch L', the shipping-rod fast at one end to the shipper and arranged to slide in a bearing in the gear-case, the cam pivotally connected with the other end of the shipping-rod and adapted to withdraw and hold the part clutch L' out of engagement with the part L, the latch having sliding connection with the shipping-rod, the spring for actuating the part clutch L', and latch, substantially as and for the purpose specified. 35

GUSTAF JERNBERG.
